UNITED STATES PATENT OFFICE.

GEORGE HILPERT, OF OTWAY, OHIO.

DESIGN FOR A PENDANT.

SPECIFICATION forming part of Design No. 24,494, dated July 23, 1895.

Application filed April 3, 1895. Serial No. 544,341. Term of patent 3 $\frac{1}{4}$ years.

to all whom it may concern:

Be it known that I, GEORGE HILPERT, a citizen of the United States, residing at Otway, in the county of Scioto and State of Ohio, have invented and produced a new and original Design for Pendants; and I do declare the following to be a full, clear, and exact description of the same, reference being had to the accompanying drawings, forming a part thereof.

My invention relates to designs for pendants for decorating purposes.

In the accompanying drawings, Figure 1 is a side view of my new design. Fig. 2 is a view of the upper end thereof. Fig. 3 is a view of the lower end.

My design comprises and the leading feature is an egg-shaped body having a series of rings 1 arranged around its circumference

and each consisting of spirally-wound ribs; 2, scrolls arranged between the rings and consisting of spirally-wound ribs; 3, a top cap consisting of a spirally and closely wound rib, and 4 the bottom cap consisting of a spirally and closely wound rib.

The design herein shown and described is very pleasing to the eye and will make a very neat and pretty Christmas-tree ornament.

What I claim is—

The design for a pendant for decorating purposes, as herein shown and described.

In testimony whereof I affix my signature in presence of two witnesses.

GEORGE HILPERT.
